UNITED STATES PATENT OFFICE.

JOHN F. KETCHY, OF DALLAS, TEXAS.

REAMER.

Application filed October 17, 1925. Serial No. 63,197.

This invention relates to reamers and refers more particularly to a device of this character to be used when reaming the bottoms of pier or post holes in building construction preparatory to the depositing of concrete therein.

An important object of this invention is the effective cutting away of the ground at the base of the hole in an inverted cone 10 shape in a simple and practical manner with the consumption of a minimum of time.

A further object is to provide a device which is readily adjustable for reaming shallow or deep holes.

An object is to provide a device which 15 may be operated by a single individual, and which utilizes leverage principles in such a manner as to make such operation readily and easily performed.

An advantage of this invention is its 20 simplicity of construction and economy of operation.

Other advantages and objects will be brought out, as well as those heretofore 25 mentioned, in the course of the following description taken in connection with the annexed drawings in which—

Figure 1 represents a side elevation of an 30 adaptation of my invention assembled in place for operation.

Figures 2 and 3 are cross-sectional and 35 front elevational views respectively of the fulcrum plate.

Figures 4 and 5 are detailed elevation and 40 cross-sectional views of the adjustable guide member.

Figure 6 shows the drilling or cutting 45 pick, and Figure 7 represents an elevation of the base of the supporting pipe member.

In the figures, the supporting member 1, 50 formed of metal piping, has secured at one end a spear shaped member 2. This member has a shaft 2^b which is tapered and is of size sufficient to enter the opening in the pipe 1, and be wedged therein. A washer 2^a is provided, also of metal, adapted to be positioned between the spear head shoulder and the pipe. The purpose of this washer is to prevent the pipe or supporting member from 55 settling down into soft ground at the time the reamer is being operated.

At the other extremity of the pipe or at a 60 position adjacent that extremity at a point preferably between three or four feet from 55 the surface of the ground is secured a fulcrum plate 3 (shown in detail in Figures 2

and 3). This plate extends laterally a sufficient distance from its point of attachment to the pipe, to provide practical working leverage. At a substantial space from the 60 end of the plate is drilled a hole 3^b. A clamp, 5, shaped as shown in the figures or in any other desired shape to best grip the pipe, when the bolts 4—4 are tightened, secures the plate to the pipe. A small hook-like projection 5^a is formed on the upper outside edge of the clamp. The heads of the bolts are sunk so that their tops are level with the plate surface. Recesses in the plate to receive these heads are designated by characters 3^a—3^a.

A suitable weight 6 is hung upon the hook 5^a to hold the pipe steady in its position in the hole, see Figure 1, to provide against the possibility of movement of the pipe 75 when severe strokes are necessary to dislodge tough, hard or rocky earth.

A lever or bar 7, is secured by adjustable clamp 8 in one of the perforations 7^a to a working bar or pipe 9. As the bar is preferably flat, a shaped handle 8^a is provided for the extremity thereof, the opposite end of the bar being secured by a bolt or other suitable member through aperture 3^b, to the plate.

The extremity of the bar extends beyond the plate, but the bar lies flat against the plate for reasons set forth more fully hereinafter.

A pick or curve pointed rod 10 is provided 90 which has a tapered upper extremity to allow insertion in lower end of pipe 9. A set screw or bolt 11 secures the pick rigidly in the pipe.

A guide member 12 having a collar 14 95 secured at one end, is itself secured to the pipe 1 by means of a U bolt 13. The member 12 has a series of curves formed in one side thereof and holes 12^a on each side of each curve adapted to receive the U bolt. 100 When the bolt is tightened it draws the guide member into rigid position on the pipe 1.

The curves and additional holes form 105 means for further lateral adjustment of the collar with respect to the pipe. The collar acts as a guide to the pick. The letters X—X show the shape of the hole after the reaming process. In operation the pipe is assembled with its spear headed support, 110 the adjustment of the working pipe and bar determined, depending upon the width of

the space that is to be reamed, and the depth of the hole *a*; the bar or lever *7* is then moved up and down by the handle *8^a*, the pipe *9* is moved by the handle movement, and the pick guided by the handle, cuts away the dirt in the bottom of the hole.

As desired, the operator moves around the hole, after lifting the pick to clear the point from contact with the dirt around the edges 10 of the hole, the handle acting as a lever against the broad flat surface of the plate, and practically without cessation of the picking operation the hole is reamed out accurately and evenly in an inverted cone 15 shape, in a very short period of time. The pipe *9* may be threaded at its upper end to allow extensions to be made, when the reaming of deeper holes is required.

It should be understood that various 20 changes in details of construction may be made to secure desired results without departing from the spirit and intent of the invention as set forth in the following claims.

What I claim is:

- 25 1. In a device for reaming the bottom of holes, a supporting member having a pointed lower extremity adapted to be seated in the bottom of the hole, a flat surfaced plate adjustably secured to the upper portion of 30 said supporting member, a lever pivotally attached to said plate parallel and touching the surface of the plate, and extending therefrom beyond the support pipe, means on said bar beyond the support pipe, for 35 pivotally and adjustably engaging the upper portion of a movable excavating member, a clamp secured to the lower portion of the supporting member, a collar in attachment to the clamp, said collar adapted to 40 guide the direction of movement of the excavating member when the lever is actuated,

and the said excavating member is raised or lowered.

2. In a reaming device for pier or post holes, a stationary member adapted to be 45 seated in the bottom of the hole, a movable excavating rod member pivotally attached to the body of a lever having its fulcrum in a plate extending from the stationary member diametrically opposite the point of 50 attachment of the lever and the movable excavating member, and means adjacent the base of the stationary member to guide the movement of the excavating rod member when the lever is actuated. 55

3. In a reamer, a supporting pipe member, a bar pivotally journaled in a plate adjustably secured to and extending laterally from the supporting pipe member at the upper portion thereof, said bar secured adjacent its central portion in pivotal attachment to a movable excavating member, and a guide in adjustable attachment to the lower portion of the supporting member, said 60 guide adapted to receive the end of the excavating member, and direct its movement. 65

4. A reamer comprising a stationary upright rod or pipe member, a plate extending laterally from the upper portion of the rod, a lever pivoted on the plate and lying 70 flush with the surface thereof, and extending therefrom past the rod and beyond it, a movable excavating member pivotally attached to the lever at a point diametrically opposite the fulcrum attachment, and means 75 on the stationary rod at a point adjacent its lower end to guide the movement of the movable member when the lever is actuated.

In testimony whereof I have signed my name to this specification.

JOHN F. KETCHLEY.
